DIPPER SHOVEL TOOTH

Stanley Seal, Flemington, N. J.

Application May 21, 1937, Serial No. 144,049

2 Claims.

(CL. 37—142)

The invention relates to a dipper or shovel tooth and more especially to a rivetless tooth and reversible point for digging dippers or shovels employed in dredgers, excavators or the like.

5 The primary object of the invention is the provision of a tooth of this character, wherein the same can be removably attached to the forward or digging edge of a dipper or shovel used in excavators, dredgers or the like machines without 10 the use of rivets or the like.

Another object of the invention is the provision of a tooth of this character, wherein the tip or point thereof is readily reversible to assure increased life in the use of the tooth and to avoid 15 uneven wear thereon as well as eliminating the possibility of the tooth becoming accidentally loosened or detached from the dipper or shovel as is the case when a tooth is riveted thereto and at the same time minimizing the expense incident 20 to the use of rivets for the fastening of a tooth to the dipper or shovel.

A further object of the invention is the provision of a tooth of this character, wherein the construction in its entirety is novel and enables 25 quick and easy attachment of the same to the shovel or dipper as well as the quick and easy reversal of the point of the tooth and additionally maintaining at all times a good point to the tooth for fast digging purposes.

30 A further object of the invention is the provision of a tooth of this character, which is simple in construction, thoroughly reliable and effective in operation, readily and easily applied, assured of firmness and security on the application 35 thereof to a dipper or shovel, maintaining a good point at all times, strong, possessed of maximum life, and inexpensive to manufacture and install.

With these and other objects in view, the invention consists in the features of construction, 40 combination and arrangement of parts as will be hereinafter more fully described, illustrated in the accompanying drawing, which discloses the preferred embodiment of the invention and pointed out in the claims hereunto appended.

45 In the accompanying drawing:

Figure 1 is a sectional view through the bottom of a dipper or shovel showing the tooth constructed in accordance with the invention applied thereto and being in elevation.

50 Figure 2 is a top plan view.

Figure 3 is a bottom plan view.

Figure 4 is a fragmentary sectional view taken on the line 4—4 of Figure 1 looking in the direction of the arrows.

55 Figure 5 is a sectional view on the line 5—5

of Figure 1 looking in the direction of the arrows. Similar reference characters indicate corresponding parts throughout the several views in the drawing.

Referring to the drawing in detail, A designates generally a portion of the bottom of a dipper or shovel employed in dredgers, excavators or other digging machinery while B denotes generally a tooth constructed in accordance with the invention employed therewith. This tooth B is formed with an elongated body constituting a shank 10 which for a portion of its length is upwardly struck from the bottom thereof to effect a central hollow 11 opening through the under or lower side thereof. At the forward end of the shank 10 is an enlarged coupling terminal 12 provided with a rearwardly directed lower slotted heel jaw 13 accommodating the forward edge of the bottom A of the shovel or dipper, the shank 10 being rearwardly tapered and at its inner smaller end is formed a downwardly offset latching tongue or lug 14 for accommodation within a substantially rectangular shaped opening 15 for fitting within a seat 16 formed in an upwardly struck keeper lip 17 formed with the bottom A and overhanging the opening 15 therein. This tongue or lug 14 is formed with a rearwardly inclined or beveled abutment edge or face 18 disposed counterseated in the opening 15 for engagement by a correspondingly inclined or beveled edge 19 of a fastening key 20 separably received in the said opening 15 and releasably fitting a wedge fastener or bolt 21 carrying a nut 22 and accommodated in the said shank 10 so that in this manner the said shank 10 of the tooth B is detachably attached to the bottom A as clearly shown in Figure 1 of the drawing.

Carried at the tongue or lug 14 is a substantially triangular shaped or an outwardly tapered reversible tip or point 23 which is bifurcated at its inner end to provide side overlap extensions 40 24 and a socket 25, respectively, the latter receiving a reduced medial web 26 formed with and projecting from the terminal 12 for the reversible interfitting engagement of the point or tip 23 with said terminal 12. This web 26 at the extension 27 thereof engages in the socket 25 while the side overlap extensions interlock with recesses 28 in opposite sides of the terminal 12 and effect the reduced web 26 thereof.

Passed transversely at the joint 29 between the terminal 12 and the point or tip 23 through suitable openings 30 and 31, respectively, in the extensions 24 and web 26 is a fastener key or bolt 32 separably securing the tip or point 23 re- 50 55

versibly attached or fixed with the terminal 12 of the tooth B. The reversing of the tooth assures a balanced or uniform wear to the upper and lower faces of the point or tip 23 when the tooth B is attached to the bottom A of the shovel or dipper.

Formed on and projecting laterally from one side of the tip or point 23 is a protective nib or guard 33 for the nut 34 of the fastening key 32 when securing the point or tip 23 interfitted with the terminal 12 of the tooth B.

The manner of fastening the tooth B to the bottom A of the shovel or dipper avoids the necessity of riveting this tooth thereto and also enables the attachment of the tooth with dispatch or its removal therefrom while the point or tip 23 is readily reversible in the interfiting thereof with the terminal 12 of the said tooth.

The bottom A at the forward edge thereof is notched at 35 for the interfiting of the jaw 13 and said bottom for eliminating any lateral play of the tooth when fastened to the shovel, dipper or the like.

What is claimed is:

1. A tooth for a digging shovel, dipper or the like having a bottom provided with an opening rearwardly of its lead edge and also having an overhang to said opening, comprising a shank

having a front jaw formation for accommodating the lead edge of said bottom, a substantially L-shaped terminal at the rear end of said shank and received in a part of the opening for hooking engagement with the overhang thereto, a plate within said opening and wedged with the said terminal for holding the latter engaged with the overhang to said opening, and a fastener passed through the plate and the shank for separably securing the same together.

2. A tooth for a digging shovel, dipper or the like having a bottom provided with an opening rearwardly of its lead edge and also having an overhang to said opening, comprising a shank having a front jaw formation for accommodating the lead edge of said bottom, a substantially L-shaped terminal at the rear end of said shank and received in a part of the opening for hooking engagement with the overhang thereto, a plate within said opening and wedged with the said terminal for holding the latter engaged with the overhang to said opening, a fastener passed through the plate and the shank for separably securing the same together, and a reversible tip interfitted with the jaw formation, the jaw formation being interfitted with the lead edge of the said bottom.
